CLAIM

The ornamental design for a folded multipurpose tool, as shown and described.

DESCRIPTION

FIG. 1 is an isometric view from the upper right front of a folded multipurpose tool, showing our new design; FIG. 2 is a top plan view thereof; FIG. 3 is a right side elevational view thereof, the left side view being a mirror image of the view shown in FIG. 3. FIG. 4 is a bottom plan view thereof; FIG. 5 is a rear end view thereof; and, FIG. 6 is a front end view thereof.
